UNITED STATES PATENT OFFICE.

JAMES I. AYRES, OF ATLANTIC, IOWA.

COMBINED SADDLETREE AND ELASTIC CHECKREIN AND BACK-STRAP HOLDER.

SPECIFICATION forming part of Letters Patent No. 716,512, dated December 23, 1902.

Application filed August 11, 1902. Serial No. 119,323. (No model.)

To all whom it may concern:

Be it known that I, JAMES I. AYRES, a citizen of the United States, residing at Atlantic, in the county of Cass and State of Iowa, 5 have invented certain new and useful Improvements in a Combined Saddletree and Elastic Checkrein and Back-Strap Holder; and I do hereby declare the following to be a full, clear, and exact description of the invention, such as will enable others skilled in the art to which it appertains to make and use the same.

This invention relates to harness, and pertains particularly to the class of elastic attachments for harness, the object of the invention being to provide a saddletree of novel and peculiar construction having contained therein an elastic checkrein and back-strap holder.

20 A further object of the invention is to provide a saddletree with a shell or barrel having a spiral spring contained therein, a checkrein-hook having an arm attached to one end of the spring and passing therethrough, and 25 a back-strap loop having an arm extending through the spring and attached to the other spring end.

A still further object of the invention is to provide a saddletree with a hollow bridge-piece or shell having guides therein and detachable caps and to provide a pair of plates working through the caps and to one end of which is secured the ends of a spring and the other ends having one a checkrein-hook and 35 the other a back-strap loop.

Various similar forms of elastic devices such as mine have been used in connection with harness; but as far as known to me said devices when used as checkrein and back-strap holders are attached to an ordinary saddletree or used independent thereof, so that the saddletree does not form any part of the holder. Hence it is my purpose to have the saddletree constitute a part of the holder, to 40 dispense with the ordinary saddle, and to substitute therefor a hollow bridge-piece to hold a pair of spring-controlled sliding plates therein, so that their ends project outside the bridge for attaching a checkrein and a back-45 strap.

50 Other objects, advantages, and improved results accruing from the special construction

and arrangement of parts will be revealed in the specification and set up in the claims to follow.

55 In the accompanying drawings, forming part of this application, Figure 1 is a perspective view of my saddletree applied to a harness. Fig. 2 is a perspective view with the saddletree stripped of its mountings. 60 Fig. 3 is a sectional view longitudinally through the saddle-bridge and spring-controlled plates. Fig. 4 is a perspective view of the hook-plate. Fig. 5 is a perspective view of the loop-plate. Fig. 6 is a sectional 65 view of a modification.

The same numeral references denote the same parts throughout the several views of the drawings.

70 The saddletree may have the usual trimmings, such as a cover and pads, and its arms 1 are provided with a slot 2 for securing the rein-rings 3 thereto. The arms 1 are joined together by a shell or barrel 4, having an increased thickness 5 extending from one arm 75 to the other the width of the arms and forming a hollow bridge between the arms, so that a tree-seat is formed at the juncture of the bridge, and the arms and the shoulders are such as to elevate the bridge out of contact 80 with the back of a horse. Guide-bars 6 are secured in one of the bridge ends, with an interval or space 7 between them, and the ends of the bridge are provided with detachable screw-caps 8 and 9, having a central aperture. 85

The harness back-strap 10 is attached to a loop 11 of a plate 12, having a slot 13 and working through the cap 8. The overdraw or checkrein 14 is secured to a hook 15 of the plate 16 and works through the cap 9 in the 90 space 7 and is prevented from turning by the guide-bars 6.

Housed by the bridge 4 and the caps 8 and 9 and encircling the plates 12 and 16 is a spiral spring 17, having one end extended 95 through and secured to the end of the loop-plate 12, and the other end is passed through the slot 13 and extended through the end of the hook-plate 16. The projecting ends of the spring not only connect the spring to the 100 plates 12 and 16, but form an abutment for the spring.

In assembling the parts the screw-caps are slid over their respective plates, the spring

secured to one of the plates, and the latter, with the spring, inserted in the bridge from one end thereof. The other plate is inserted from the other end of the bridge through the 5 guide-bars and the spring, and the other end of the spring is passed through the end of this plate, whereby the spring and plates are connected. Then the caps are screwed in position on the ends of the bridge.

10 It is obvious that the plates are permitted to slide upon each other by the end of the spring sliding in the slot 13 and that the spring equalizes the pull between the check-rein and back-strap. There being a direct 15 connection between the checkrein and the back-strap they work independent of the saddletree, and the position of the latter is not changed or disturbed by such working. It will be seen that the saddletree is free to seat 20 itself according as occasion may demand without interfering with the spring tension or the operation of the spring on the checkrein and back-strap.

The manner of assembling the parts and 25 their connection with the saddletree will be found most simple and convenient and readily operated for repairing or adjustment, and the parts are well protected from dust, rust, and corrosion by the bridge and its caps.

30 Referring to the modification shown in Fig. 6, the hook-plate 18 is provided with a pin 19 to work in the slot of the loop-plate and against which one end of the spring works; otherwise the device is the same as that here- 35 inbefore described and the operation is the same.

Having thus described my invention, what

I claim as new, and desire to secure by Letters Patent, is—

1. A harness-saddletree having a hollow 40 bridge and screw-caps combined with an elastic checkrein and back-strap holder contained in the bridge and comprising a strap-loop plate working through one of said caps, a checkrein-hook plate working through the 45 other cap, and a spiral spring surrounding and connecting the plates slidably together.

2. A harness-saddletree having a hollow bridge and apertured screw-caps to close the bridge, combined with an elastic checkrein 50 and back-strap holder contained in the bridge and comprising a plate working through one of the caps and having a loop and a slot, a plate working through the other cap and having a hook, and a spiral spring surrounding 55 the plates and having one end secured to the loop-plate and the other end projected through said slot and secured to the hook-plate.

3. An elastic checkrein and back-strap 60 holder, comprising a plate having a loop and a slot extending from the loop, a plate having a hook and slideable over the slot, and a spring surrounding the plates and having one end secured to the loop-plate and the other 65 end passed through the slot and through the hook-plate, whereby the plates are slidably connected and elastically controlled.

In testimony whereof I affix my signature in presence of two witnesses.

JAMES I. AYRES.
